UNITED STATES PATENT OFFICE

ERIK G. GRUNDSTROM, OF CHICAGO, ILLINOIS

MOLD

Application filed August 7, 1929. Serial No. 384,051.

This invention relates to improvements in the method of and apparatus for molding or die casting metals which are normally non-malleable by applying the forming pressure to the material while the metal is in a molten state. Principally my improvements relate to the forming of articles of metals such as aluminum alloys which are non-malleable when solid but can be formed into the desired shape by applying a molding pressure while the metal is in a molten condition.

In carrying out the present invention, the molten metal is introduced directly into a lower die cavity and an upper plunger is then brought down to cause the metal to flow and take the shape of the molded article. Various means have heretofore been proposed to mold articles in such a manner, but adequate provision has not been made to permit the escape of the air and the excess metal and at the same time cause the metal to fill the mold. Thus it is customary to provide a recess which outwardly extends from the edge of the formed article to permit the escape of the excess metal, thus leaving a continuous flash which must be subsequently removed. It is also customary to use a substantially large size gate opening at one point which receives the excess metal.

It is an object of the present improvements to permit the escape of the air and excess metal through a plurality of relatively restricted passageways which uniformly surround the formed article and lead outwardly therefrom. By such a provision of vent openings, the metal is caused to flow evenly to every part of the mold.

It is further an object of the present invention to provide improved apparatus for molding articles of special shape, such as, for example, an article having a horizontally extending rim and a vertically extending cylindrical rim that is inwardly spaced from the outer edge of the horizontal cylindrical rim. In the improved apparatus the lower mold block is formed with a plurality of radially extending narrow vent openings which outwardly lead from the die cavity, and secured to the lower mold block in such a manner as to cooperate with the die plunger

to form the vertically extending cylindrical rim is a pair of relatively openable half ring members, the inner vertical edge of the ring members being formed with a plurality of recessed vent openings of relatively narrow size which outwardly lead from the cylindrical vertical rim of the formed article. By such an organization, the air and the excess metal is permitted to extrude both through the outwardly extending radial vent openings and also upwardly through the vertically extending vent openings, and the completed article may be readily removed from the mold after the retraction of the plunger by opening the half ring members.

It is further an object of the present invention to provide improved molding apparatus of the type just described in which a circular gutter is formed in the cooperating ring portions just above the vertically extending vent recesses, whereby the excess metal is permitted to collect in the gutter and to form upwardly extending from said gutter, at points intermediately spaced from the vent recesses, a plurality of additional vent recesses to permit the escape of the air.

Further objects and advantages of the present improvements will be more readily apparent from the following description taken in connection with the attached drawings, which illustrate preferred embodiments of my improved molding apparatus, in which—

Figure 1 is a vertical sectional elevation taken through the closed mold and illustrating the formation of the articles, the section being taken in such a manner as to most clearly illustrate the construction;

Figure 2 is a vertical elevation illustrating the plunger in raised position and the mold in section on the plane indicated by 2—2 in Figure 3, the plane 2—2 being substantially at right angles to the plane of the section shown in Figure 1;

Figure 3 is a top plan view of the lower mold with the right-hand half ring member shown in partially opened position to more clearly illustrate the construction; and

Figure 4 is a vertical sectional elevation through a mold of modified construction for forming a slightly different shape of article.

First having reference to the apparatus shown in Figures 1, 2 and 3, it will be noted that the article 10 which is being formed is a cover member and includes a recessed body portion 11 which extends to a horizontal cylindrical rim 12 and also to a vertical cylindrical flange 13 which is inwardly spaced from the outer edge of the rim 12. My improvements are especially adaptable to the formation of articles of metals which are relatively non-malleable and may be most readily formed into shape by causing the metal while in the molten state to flow to take the shape of the formed article. As an instance of metal that may be formed by the present method and apparatus, I may use an aluminum alloy. The molten metal to form the article 10 is placed in the recessed cavity 14 of the lower die member 15. From the outer rim of the cavity 14 extend substantially small size radial recesses 16, for a purpose which will be later more clearly apparent.

The plunger member 17 may be arranged to be moved by some suitable means into cooperation with the lower mold block 15. The plunger 17 includes the head 18 having bolts 19 extending therethrough to attach the upper die member 20, which is so formed as to cooperate with the lower mold block 15 to form the article 10. The die 20, therefore, includes a cylindrical portion 21 to form the rim 13 of the article 10. It is apparent that additional mold blocks must be provided in order to form the rims 12 and 13. I therefore show a pair of cooperating clamp members 22—22. As will be apparent from Figures 2 and 3, the members 22 include pivot ears 23—23 which are positioned by the bushing 24 having a bolt 25 extending therethrough and screw-threaded to an opening 26 formed in the lower mold block 15. A washer 27 surrounds the bolt 25 and seats against the upper pivot ear 23, as will be evident from Figure 2, and a lock nut 28 is provided to securely hold the parts in engagement. The members 22 are adapted to close at their front ends, as shown in Figure 3, about a corresponding pivot bolt 29, which has a screw-threaded portion 30 engaging the opening 31 formed in the mold block and associated with the holding washer 32 and the lock nut 33. Suitable handles 34—34 may be secured to the members 22 to permit their being readily swung about the pivot 25.

As additional means for holding the members 22 in molding position, I may form the lower mold block 15 with the outwardly extending lugs 35—35 beneath which the blocks 36—36 will be engaged. The blocks 36 are arranged to be carried by the members 22 by providing the downwardly depending plates 37—37, which are secured to the members 22 by the bolts 38. Additional bolts 39 hold the blocks 36 to the plates 37. Thus when the members 22 are in closed position

and the lock nuts have been tightened, the members 22 are forced into tight contact with the mold block 15 and cooperate with the radial recesses 16 to form vent passageways outwardly leading from the horizontal rim 12 of the formed article. As additional means for permitting the escape of the excess metal and of the entrained air, I may form the inner cylindrical surface of the members 22 with a gutter recess 40, which is intermediately spaced between the upper and lower surfaces of the members 22. The gutter 40 has connections to the rim 13 of the formed article by the plurality of vertically extending recesses 41, which are uniformly spaced about the rim 13. The gutter also has communicating vent openings to the outside by means of the recessed passageways 42, which are substantially narrower than the passageways 41 and intermediately spaced relative to the passageways 41.

In the operation of the apparatus, the molten metal will be placed in the cavity of the lower mold block 15 after the members 22 have been suitably clamped into position. The plunger 17 is then brought down and causes the metal to flow to take the shape of the mold. The metal will be caused to flow evenly to the extreme edges of the mold. The recesses 16 are of such small size that only air will be permitted to escape therethrough. The vertical openings 41 permit the escape of air and finally allow the excess metal to be extruded and collect in the gutter 40. The plunger is then retracted and the completed article may be removed after the clamp mold blocks 22 have been swung to open position.

Figure 4 illustrates an apparatus generally similar to that described, but adapted to form a different shape of article. The article 50 is a cup-shaped member having a single circular rim 51. It is obvious that it will only be necessary to provide the vertical vent openings 41 together with the gutter 40 and the vents 42. The operation will be similar in every other respect to that previously described.

As characteristic of my improved method it may be stated that the air is permitted to escape during the molding operation through a plurality of restricted passages uniformly spaced about the edge of the mold. If the air is allowed to escape too freely at certain points, the metal will not flow evenly, but in my method the restricted vents permit an even distribution of the metal to the extreme edges of the mold.

Various changes and modifications may be resorted to without departing from the spirit of my invention as expressed in the appended claims.

I claim—

1. Apparatus for molding articles of metal which is normally non-malleable comprising

a lower forming member having a die cavity therein and an upper forming member adapted to be moved to cooperate with said lower forming member to cause the metal in a molten state to flow and take the form of the mold, said lower forming member including a portion upwardly extending from the top edge of the formed article and having formed therein a plurality of recesses adapted to cooperate with said upper forming member to form a plurality of restricted passages permitting the escape of the gases and the excess metal.

2. Apparatus for forming articles from metal normally non-malleable by molding the metal in a molten state, which comprises a lower forming member having a die cavity therein, an upper forming member having a die portion adapted to cooperate with the die cavity of the lower forming member, said lower forming member having a plurality of passages outwardly leading from the upper edge of the formed article to permit the escape of gases.

3. Apparatus for molding articles from metal in a molten state which comprises a lower mold block, an upper mold block, said mold blocks being mounted for relative movement, a pair of cooperating mold pieces adapted to be secured to said lower mold block and to closely cooperate with the sides of said upper mold block, said mold pieces including a plurality of vertical recesses adapted to cooperate with the sides of said upper mold block to form a plurality of restricted vent passages outwardly leading from the upper edge of the formed article.

4. Apparatus for molding articles from metal in a molten state which comprises a lower mold block, an upper mold block, said mold blocks being mounted for relative movement, a pair of cooperating mold pieces adapted to be secured to said lower mold block and to closely cooperate with the sides of said upper mold block, said mold pieces including a plurality of vertical recesses adapted to cooperate with the sides of said upper mold block to form a plurality of restricted vent passages outwardly leading from the upper edge of the formed article, said lower mold block including a plurality of recesses formed on its upper surface adapted to cooperate with the lower surface of said mold pieces to form a plurality of additional vent passages outwardly leading from an edge of the formed article.

5. Apparatus for forming molded metal articles which comprises a lower metal block having a die cavity therein, an upper mold block mounted for relative movement into cooperation with said lower mold block, mold pieces pivoted to said lower mold block, and means for securing said pivoted mold pieces in closed position closely surrounding said upper mold block upon its movement into a

molding position, said upper mold block and said pivoted mold pieces forming therebetween a plurality of substantially vertical restricted vent passages.

6. Apparatus for forming molded metal articles which comprises a lower metal block having a die cavity therein, an upper mold block mounted for relative movement into cooperation with said lower mold block, mold pieces pivoted to said lower mold block, and means for securing said pivoted mold pieces in closed position closely surrounding said upper mold block upon its movement into a molding position, said upper mold block and said pivoted mold pieces forming therebetween a plurality of substantially vertical restricted vent passages, and said lower mold block and pivoted mold pieces forming therebetween a plurality of substantially horizontal restricted vent passages, said vent passages permitting the escape of gases during the molding operation.

7. Apparatus for molding metal articles comprising a lower forming member having a die cavity therein, an upper forming member adapted to be moved to cooperate with said lower forming member to cause the metal, in a molten state, to flow and take the form of the mold, one of said forming members having a plurality of spaced recesses adapted to cooperate with the other forming member to form a plurality of restricted passages permitting the escape of the gases and excess metal.

Signed at Chicago, Illinois, this 1st day of August, 1929.
